[57] CLAIM

The ornamental design for a Shepherd's hook, as shown and described.

DESCRIPTION

FIG. 1 is an isometric view of a Shepherd's hook showing our new design;

FIG. 2 is an enlarged, fragmented perspective view thereof;

FIG. 3 is a front view thereof;

FIG. 4 is a side elevation view, the opposite side view being a mirror image thereof.

FIG. 5 is a top view thereof; and,

FIG. 6 is a bottom view thereof.

The view of FIG. 2 is shown fragmented for clarity of illustration.
